TOY DONKEY BANK

Leonard Florence, Revere Beach Parkway, Chelsea, Mass.

Filed Feb. 2, 1960, Ser. No. 59,241

Term of patent 14 years

(Cl. D34—11)

FIG. 1

FIG. 2

FIG. 3

The essential feature of my design resides in the head portion as shown.

I claim:

The ornamental design for a toy donkey bank, as shown and described.
